UNITED STATES PATENT OFFICE.

OSCAR C. JULIEN, OF MONTREAL, WISCONSIN.

DRILL-FORMING DIE.

1,230,303.

Specification of Letters Patent. Patented June 19, 1917.

Application filed April 26, 1916. Serial No. 93,755.

To all whom it may concern:

Be it known that I, OSCAR C. JULIEN, a citizen of the United States, residing at Montreal, in the county of Iron and State 5 of Wisconsin, have invented certain new and useful Improvements in Drill-Forming Dies, of which the following is a specification, reference being had to the accompanying drawings.

10 This invention relates to machines for forging and sharpening rock drills and other drill bits, and particularly to those machines which have vertically operating clamping dies and a horizontally operating upsetting 15 hammer, such machines, for instance, as the Sullivan drill sharpening machine, whose construction is illustrated in the Patent No. 1,123,372, granted to T. H. Proske, January 5, 1915, though the invention is not limited 20 to use with this particular machine.

In these machines, a steel rod is automatically upset by the upsetting hammer and forged by vertically operating forging hammers and dies so as to form a head on the 25 rod, which head, if the work is a drill bit, is formed with sharpened radiating wings. The work of upsetting is done by "dollies" which receives the impact of a pneumatic hammer, the steel rod being held by clamping dies during the upsetting process. The 30 steel rod is upset and then removed from the clamping dies and disposed beneath the forging dies until the drill is completed.

The steel is partially upset by a few rapid 35 blows of the "dolly" and then the operator, without changing the position, brings the bit under the vertical hammer and here the wings and corners of the bit are drawn out under swaging dies. The bit is thus ham- 40 mered out alternately under the two hammers until it is upset to the proper gage and shape and the wings, corners and cutting edge drawn out so that they are uniform and of the right thickness and angle. One 45 "dolly" is required for each shape and each gage of bit to be made and one set of clamping dies required for each diameter of steel rod.

Now if it be desired to make a bit having 50 a head of a diameter of $2\frac{1}{2}$ inches from a steel rod having a diameter of $\frac{7}{8}$ of an inch,

it is necessary to start with a "dolly" of $1\frac{3}{4}$ inches in diameter. This in one heat will form a bit having a head of $1\frac{3}{4}$ inches in diameter, but in order to increase the diameter of the head it is now necessary to change the "dolly" and the clamping dies and proceed in this manner by changing the clamping dies and "dolly" until the complete size has been made. In the example referred to 55 here, this would require four heats and three changes of "dollies," and even then a perfect bit could not be made by reason that the steel in the operation bends over to one side of the clamping dies and so causes flaws in the 60 steel.

The general object of my invention is to provide a pair of coacting clamping dies so formed that the steel as it is being upset will be at all times supported against this lateral 70 bending action from the first blow of the "dolly" until the last, and a further object of this invention is to provide means permitting a relatively large head or bit to be made or upset on a relatively small steel shank 75 without a change of the "dollies" or clamping dies and at one heat.

A further object of the invention is to provide a very simple clamping die for this purpose which may be used on a large variety of 80 machines working on this principle, which does not require any changes in the machine itself, and which has been found very effective in practice.

Other objects will appear in the course of 85 the following description.

My invention is illustrated in the accompanying drawings, wherein:

Figure 1 is a longitudinal section of a drill forming and sharpening machine of the 90 character heretofore referred to;

Fig. 2 is an enlarged vertical section on the line 2-2 of Fig. 1;

Fig. 3 is a fragmentary enlarged top plan view of the cross head 14, the dolly and the 95 dolly operating hammer;

Fig. 4 is a top plan view of the lower section of my improved clamping die;

Fig. 5 is a longitudinal sectional view on the line 5-5 of Fig. 7 showing the drill supporting jaws in a fully retracted position; 100

Fig. 6 is a longitudinal sectional view on

the line 6—6 of Fig. 7, showing the drill supporting jaws in a partially retracted position;

Fig. 7 is an end view of the two sections of the clamping die and the jaws;

Fig. 8 is a longitudinal sectional view through one of the drill supporting jaws and its section 32;

Fig. 9 is a face view of one of the sleeve sections upon which the drill supporting jaws are pivoted;

Fig. 10 is a longitudinal sectional view through the clamping die and in the nature of a diagram, showing the position of the parts at the beginning of the drill forming operation;

Fig. 11 is a like view to Fig. 10 and showing the position of the parts when the drill is partly formed;

Fig. 12 is a like view to Fig. 11 but showing the position of the parts when the drill is still further formed;

Fig. 13 is a like view to Figs. 10, 11 and 12, but showing the position of the parts when the drill is fully formed;

Fig. 14 is a section on the line 14—14 of Fig. 4;

Fig. 15 is a fragmentary cross section of the drill supporting jaws on the line 15—15 of Fig. 8;

Fig. 16 is a perspective view of the dolly.

Referring particularly now to Fig. 1, which illustrates the machine to which my invention is applied, 10 designates a base of any suitable character having a bed plate 11 upon which is mounted one half of a clamping die, the half section of the clamping die being designated 26, and mounted on suitable steel rods 13 above the section 26 of the clamping die is a movable cross head 14 carrying the other section 26^a of the clamping die. The cross head 14 is moved toward the bed plate by means of a toggle link 15 which is connected to a slideable cross head 16 in turn connected by the members 13 to the cross head 14, the upper end of this toggle link 15 being connected to a slide 17 in turn connected to a piston 18 operating in a chamber 18^a, this piston being forced forward or rearward by means of compressed air or other suitable motive fluid, the connections, however, for this purpose not being shown. When the piston is forced forward it is obvious that the cross head 16 will be depressed, carrying with it the cross head 14, and that the upper section 26^a of the clamping die will be brought down toward and in clamping engagement with the section 26 of the die and in clamping engagement with the rod which may be placed between the sections of the clamping die.

Operating in conjunction with the clamping die sections 26 and 26^a is a "dolly" 19

which is loosely mounted upon a distance 65 piece or rod 20 which in turn receives the impact of a piston-like hammer reciprocating within a cylinder 21 and operated by compressed air. Here again it is not deemed necessary to illustrate the valve 70 mechanism whereby the reciprocation of the piston is secured.

Mounted in advance of the clamping dies and the cross heads are forging dies designated 22 and 24, one of which is fixed upon a suitable anvil 23 in turn fixed to the bed plate of the machine, the other 24 being fixed to a vertically reciprocating hammer 25, the shank of which is connected to any suitable compressed air operating mechanism. The dies 22 and 24 are used for swaging the bit from time to time as will hereafter more fully appear. I have not illustrated the various levers whereby compressed air is admitted to the swaging cylinder and the "dolly" operating cylinder as these are well known and form no part of my invention. It is sufficient to say that under normal circumstances the steel is placed between the clamping dies, the piston 18 is operated to 90 cause the clamping dies 26 and 26^a to approach each other and thus clamp the steel, the hammer 21 is then operated to cause blows to be struck upon the "dolly" which upsets the steel into the dies 26 and 26^a, and 95 that in the ordinary operation of this mechanism after some strokes of the "dolly" upon the steel the clamping die is released and the steel disposed between the swaging dies which are then operated to forge the 100 head which is partly formed upon the end of the steel, and the steel is then placed back in the clamping die and the "dolly" is again operated.

My invention relates particularly to the 105 peculiar construction of the clamping die whereby as the steel is being upset the steel will be always supported so that it can not bend. To this end, I form each section of the clamping die as illustrated in Fig. 4, 110 that is, as a semi-cylindrical member 26 or 26^a having a relatively large head and a reduced shank. The interior of the clamping die is chambered, as at 27, this chamber extending from the forward end of the clamping die nearly to the rear end thereof and terminating in a shoulder 28 from which extends a relatively contracted bore 29 which is semi-cylindrical in form or semi-octagonal or hexagonal, depending upon 115 the cross section of the steel to be operated on. As illustrated, this bore 29 is semi-hexagonal. The side wall of the chamber 27 gradually diverges inward from the forward extremity of the die to a point about midway of the chamber 27 and then again converges. This diverging side wall is 120 designated 30. At a point 31 the chamber

27 has the same diameter as at the mouth of the chamber and from this point 31 to the shoulder 28 the chamber has a diameter the same as the mouth of the chamber.

5 Mounted within the chamber 27 are the semi-circular sleeve sections 32 having an exterior diameter approximately equal to that part of the chamber between the numeral 31 and the shoulder 28 and each having a semi-cylindrical recess 33 approximately equal in diameter to the bore 29. Hingedly mounted upon each section of the sleeve 32 are the movable jaws 34 illustrated in Fig. 7 as two in number, each jaw in 10 cross section being a segment of a circle and the free ends of the jaws being capable of movement outward or inward from or to or toward the axis of the clamping die. The detailed manner in which the jaws 34 are 15 hingedly connected to the sleeve sections 32 will be later described.

Extending longitudinally through each semi-cylindrical die section 26 is a T-shaped slot 35, this slot extending inward from the 20 forward end of the die to a point slightly outward of the shoulder 28 and this slot intersecting the wall 30 of the chamber 27. Each section 26 of the sleeve is formed with a radially projecting T-shaped lug 36 which 25 engages in the T-shaped slot 35 and thus the sleeve sections 32 are movable longitudinally of the die sections 26 and held from any rotative movement and also are held centered within the chamber 27, as most clearly 30 shown in Fig. 7. The extremities of the segmental jaws 34 have pivoted thereto T-shaped members 37 which engage in T-shaped slots 38 also formed in the wall of the chamber 27, these slots 38, however, 35 extending inward parallel to the portion *a* of the wall 30 and terminating slightly beyond the point *c* of the largest diameter of the chamber 27. It will thus be seen that when the sleeve 32 is disposed so that the ends of 40 the segmental jaws are approximately flush with the outer end of the die sections 26 (see Fig. 10) the jaws will be forced inward so that the interior curved faces of the jaws will define a bore approximately of the same 45 diameter as the bore formed by the conjoined recesses 33, but that as the sleeve 32 moves rearward within the chamber 27, the free ends of the segmental jaws 34 will be drawn outward by the engagement of the T-shaped members 37 with the slots 38 and 50 that these jaws will continue to expand as the sleeve and the jaws move inward until eventually the jaws will rest upon the portion *b* of the chamber 27 in the position 55 shown in Fig. 13. At this time the sleeve formed of the two sections 32 will be disposed in the portion *d* of the chamber 27.

Each section of die 26 is provided on its base with a bore 39, and a coil spring 40 is

disposed in this bore and extends into a 65 socket 41 formed in the inner face of the sleeve or base section 32. Each sleeve or base section 32 is also provided with a shank 42 which is received in a bore 43 formed in the corresponding die section 26, and the extremity of this shank is formed with a notch 44 which is adapted to be engaged by a latch designated generally 45 when the sections 32 of the sleeve have been forced rearward sufficiently far so as to bear against 70 the shoulder 28. It will be understood of course that the spring 40 acts to urge its corresponding sleeve section 32 outward so that the jaws are approximately flush with the end of the corresponding die section 26. 75

The manner in which the jaws 34 are pivotally mounted upon the sleeve section 32 is illustrated best in Figs. 5, 6 and 9. Preferably, the sleeve sections 32 are semi-hexagonal in form, and preferably the jaws 34 80 are segments of a hexagon adjacent their hinged ends, but are sections of a circle from about the middle of the jaws to the extremities thereof, as this permits a better pivotal or hinged engagement between the jaws and 85 the sleeve sections 32 than would be possible if the sleeve sections 32 were segments of a circle and the jaw sections 34 were also segments of a circle. The outer end of each sleeve section is formed with outwardly extending lugs 46 and between the lugs and on each side of the lugs the end face of the sleeve section is hollowed out at 47. Each jaw 32, as before stated, is segmental in 90 cross section, and preferably the segment is a hexagon adjacent its hinged end, and its inner hinged end is bifurcated or slotted as at 48 to receive the corresponding lug 46, the end wall of this slot being outwardly 95 flared. The inner end face of each jaw is beveled or rounded, as at 49, (see Fig. 6), and the confronting hollowed out face of the sleeve section is correspondingly rounded so that the jaw which is pivoted to the lug 46 100 by a pin 50 may swing out against the face *b* of the die section 26. The free end of each jaw 34 is formed with a longitudinally extending recess 51 on its outer face which intersects the adjacent end face of the jaw, and pivotally mounted in this recess is the 105 disk-shaped inner end 52 of the corresponding T-shaped keeper or member 37, previously referred to, the head of which engages 110 in the slot 38.

It will thus be seen that if the sleeve sections 32 be forced gradually rearward into the chamber 27, the free ends of the jaws will be gradually drawn radially outward or in divergent relation to each other until 115 eventually the sleeve sections 32 will abut against the shoulder 28 which is the position shown in Fig. 13. This movement of the sleeve sections will of course be resisted by 120

the springs 40. When the sleeve sections have been forced fully inward, each latch or detent 45 will engage with the corresponding notch 44 of the shank 42 and hold the parts in this position until the latches are released. Each latch 45 has a shank 53 which is disposed in the recess 54 formed in the rear end face of the corresponding die section 26, and the shank is guided upon a pin 55. A spring 56 urges the latch toward the bore 43, but the latch may be manually withdrawn from its engagement with the notch 44, the latch being formed with a finger piece to this end.

15 Before describing the particular construction at the forward ends of the jaws, it is necessary to describe the "dolly" used with my construction. The "dolly" 19, which is illustrated in Fig. 16, has practically the 20 shape of the "dolly" ordinarily used for forming or sharpening drill bits, and consists of a block of tool steel, square as regards its base 57 but having a central extension 57^a which, as illustrated, is cylindrical 25 and has an exterior diameter equal to the diameter of the chamber 27 at its mouth. The square base is bored to receive the impact transmitting member or rod 20, as shown in Fig. 1. The face of the "dolly" 30 is formed with intersecting V-shaped grooves 58, or is otherwise shaped to form a proper cutting end face on the steel which is to form the bit. "Wet dollies," that is, 35 those intended to be used for hollow steel are formed as shown in Fig. 16 with a central steel pin 59 which enters the bore of the steel and keeps the bore open. In order to fully support the steel while it is being 40 operated upon by the dolly, I form each jaw 34 at its extremity with an extension 60 triangular in section to fit in one of the triangular grooves 58 and as the jaws expand with the expansion of the steel, these 45 triangular lugs or extensions 60 travel radially outward in the grooves 58 of the dolly.

50 In order to retract the dolly after the impact of the distance piece or rod 20 thereon, which distance piece in turn receives its impact from a piston-like hammer operating within the chamber 21, there are ordinarily 55 provided dolly springs having the angular form illustrated in Fig. 3. These dolly springs at their rear ends are connected ordinarily to any fixed portion of the machine, the opposite ends of the springs being coiled and then extended at right angles and removably inserted in the dolly. These 60 springs act to retract the dolly after each impact of the distance piece and prevent the dolly sticking within the opening of the die. When a new dolly is used, the forward ends of the springs are withdrawn from engagement with the old dolly and the 65 new dolly is put in place and the springs

again engaged. In the ordinary dolly, the holes 66 for the reception of the forward ends of the dolly springs are disposed 4" from the rear end of the dolly. In the dolly used with my improved die, the holes are 70 approximately 2" from the rear end of the dolly and hence I can not use the ordinary dolly springs, at least in the position which they ordinarily occupy and, therefore, I provide an extra pair of dolly springs design- 75 nated 61 in Fig. 3, the rear ends of which are mounted upon the collars 62, these collars being shiftable upon the longitudinally extending rods 63 which hold the heads of the piston cylinder 22 in place. These rods are 80 not illustrated in Fig. 1 as they are commonly found on this class of drill formers or sharpeners, but these rods are illustrated in the patent to Proske, 1,123,372, before referred to and are illustrated in Fig. 3 of 85 the annexed drawings. By this construction, I am able to detach the springs 61 from engagement with the dolly 19 and shift the collars 62 and the springs rearward upon the rods 63 so as to get them out of the way 90 so that the regular springs may be used with the ordinary dolly and die.

In order to cover the ends of the slots 35 and 38, I countersink the ends of the die sections 26 and provide a cover plate for 95 each die section designated 67 which cover plate is disposed in this countersink and held in place by screws 68.

In ordinary use and where the steel to be used is hexagon steel $\frac{5}{8}$ of an inch in diameter, the bore 29 of the clamping die 26 is hexagonal in shape and $\frac{7}{8}$ of an inch in diameter when the clamping dies are together. While the bore 33 of the sleeve formed by the sections 32 is one inch in 105 diameter and has a driving fit on the steel, it will of course be obvious that these dies may be varied in internal diameter to suit steel rods having different diameters and that in this case the internal diameter of the 110 sleeve formed of the sections 32 will also be greatly varied.

The operation of this invention is as follows: The steel which is heated to a yellow heat for about six inches from its extremity 115 is placed between the clamping dies 26 and the vise formed by the clamping dies is closed by admitting air behind the piston 18. The steel is thus firmly held with a very great pressure and the clamping die sections 120 thus form a vise holding the steel firmly in place against bodily longitudinal movement under the impact of the "dolly." After the clamping dies are set, the steel is partially upset by a few rapid blows of the hammer 125 on the "dolly." The "dolly" it will be seen, has a diameter equal to the exterior diameter of the sleeve formed by the sleeve sections 32 and hence the impact of the "dolly" 130 will not only compress the steel rod and tend

to upset the end of the steel rod, but it will likewise strike the ends of the jaws 34 so that as the material of the steel rod is forced inward and laterally expanded the jaws will also be forced inward and will be laterally expanded both by reason of the pressure of the expanded metal rod and also by the fact that the members 37 will draw the jaws positively outward by the engagement of these members 37 with the inclined grooves 38. Thus the continual lateral expansion of the metal will be permitted by the continual lateral expansion of the jaws until eventually the sleeve sections 32 will be forced to the rear end of the chamber 27 and against the shoulder 28 when the jaws will have been expanded to their greatest amount and the head of the drill will be formed.

While I have above described the action of the "dolly" on the steel rod as if this action was continuous until the head of the drill was completely formed, yet in the ordinary operation of forming the head of the bit or drill the steel is alternately submitted to the action of the "dolly" and the swaging dies 22 and 24. Inasmuch as the form of these swaging dies is well known and their operation well understood, it has not been deemed necessary to illustrate these swaging dies in detail, and it is believed sufficient to say that these swaging dies act to form in the head of the bit the longitudinally extending V-shaped grooves which define the wings of the bit. Thus in the actual operation of forming a bit after the steel has been partially upset by a few blows of the "dolly" the clamping dies are opened and the operator brings the partially worked steel under the swaging dies and the swaging dies draw out to a certain extent the wings at the corners of the steel. The steel is then again placed within the "dolly" and a further operation performed thereon, when it is again placed between the swaging dies, and so on until the steel is upset to form a bit of the proper gage and shape and the wings, corners and cutting edges drawn out so that they are uniform and of the right thickness and angle, it being of course understood that the "dolly" acts to shape the cutting edges of the wings of the bit.

While I have above described the ordinary operation of forming the bit, as usually practised, it is to be understood that where it is possible my device may be used for forming the head and cutting edges on the steel without alternately submitting the steel to the action of the swaging dies. It is to be noted at this point that the latches 45 act to hold the sleeve sections 32 and the jaws in their final position so that the clamping dies may be removed from the steel, the steel placed beneath the forging dies, and

then the steel replaced within the clamping dies and again operated on by the "dolly" or without the necessity of reheating the steel, this last action of the "dolly" being to finish and perfect the bit. 70

Having described the invention, what I claim is:

1. In a mechanism for upsetting the ends of rods, an angular rod clamping die including members longitudinally movable and coincidentally angularly shiftable in relation to the longitudinal axis of the die. 75

2. In a mechanism for upsetting the ends of rods, a rod clamping die including a sleeve and radially expansible members pivotally mounted on the sleeve and longitudinally movable with the sleeve. 80

3. In a mechanism for upsetting the ends of rods, a rod clamping die, and means associated with the clamping die for supporting and at all times engaging the side faces of the rod against bending while the rod is being upset, said means being movable radially outward and longitudinally by and with the expansion of the head of the rod as it is being upset. 85

4. In a mechanism for upsetting the ends of rods, a rod clamping die, and means disposed within the clamping die for supporting the side faces of a rod against bending while the rod is being upset, said means being radially and longitudinally movable. 95

5. In a mechanism for upsetting the ends of rods, a rod clamping die formed in two coacting sections, a dolly reciprocable into and out of the die and against the head of a rod clamped therein, and means disposed within the rod clamping die for supporting the side faces of the rod and holding the rod against bending while it is being upset, said means being longitudinally movable into the die and radially movable with relation to the rod as the rod is upset. 100

6. In a mechanism for upsetting the ends of rods, a rod clamping die having a chamber formed therein adapted to receive a reciprocating dolly, means within the clamping die for supporting the side faces of the rod clamped therein and being upset, said means being radially movable into angular relation to the axis of the rod, the wall of the chamber in the die being formed for co-active engagement with and to support said means at all stages of radial outward movement. 110

7. A mechanism for upsetting the ends of rods including a rod clamping die having a chamber formed therein, the side walls of which extend divergently inward for a distance and then converge to a diameter equal to that of the opening of the chamber and then extend inward with a uniform diameter, and radial and longitudinal rod supporting members mounted within the chamber and bearing against the walls thereof, 125

said members being adapted to closely surround and support the head of the rod to be upset and to be driven in as the head of the rod is longitudinally compressed and its diameter increased.

8. In a mechanism for upsetting the ends of rods, a clamping die having a chamber formed therein, the side walls of the chamber extending inward divergently for a distance equal to the upsetting head to be formed on the rod, the walls then converging to a diameter equal to that of the opening of the chamber and then extending inward with a uniform diameter, a sleeve supported within the clamping die for longitudinal movement, and a plurality of rod supporting members pivotally mounted on the sleeve for radial swinging movement.

9. In a mechanism for upsetting the ends of rods, a rod clamping die having a chamber formed therein, the side walls extending inward divergently for a distance and then converging to a diameter equal to that of the opening of the chamber and then extending inward with a uniform diameter, the side walls of said chamber being formed with a plurality of longitudinally extending T-shaped grooves parallel to the axis of the die, and being formed with a plurality of T-shaped grooves extending parallel to the inwardly divergent portion of the chamber, a sleeve mounted within the chamber for longitudinal movement therein and having T-shaped lugs engaging the first-named grooves, a plurality of rod supporting members or jaws pivotally mounted upon the sleeve for radial movement, and a plurality of members pivotally mounted upon said jaw members and having T-shaped heads engaging each in one of the second named grooves.

10. In a mechanism for upsetting the ends of rods, a rod clamping die having a chamber formed therein and opening upon the end 45 of the die, said chamber extending inward divergently for a distance and then converging to a diameter equal to that of the opening of the chamber and then extending inward with a uniform diameter, the die being formed rearward of said chamber to clamp a rod extending through the chamber, a sleeve mounted within the chamber for longitudinal movement and having a bore slightly greater than the diameter of the rod to be operated on, and a plurality of segmental jaws pivoted to said sleeve for radial movement, said segmental jaws when extended parallel to the axis of the sleeve defining a bore slightly larger than the rod 55 to be operated on, and means for causing the divergence of the jaws as the sleeve is forced inward into the chamber, said means acting to support the jaws.

11. In a mechanism for upsetting the ends of rods, a rod clamping die having a

chamber formed therein, said chamber opening upon the end of the die and extending inward divergently for a distance and then extending inward convergently for a distance and then having a uniform 70 diameter, rod supporting means disposed within the chamber and movable longitudinally therein and including a plurality of pivoted jaws adapted to move into divergent position as they move toward the rear end of the chamber, and releasable means for latching said first-named means in its fully retracted position.

12. In a mechanism for upsetting the ends of rods, a rod clamping die having a 80 chamber formed therein, the side walls of which extend inward divergently for a distance, and then converge to a diameter equal to that of the opening of the chamber and then extend inward with a uniform 85 diameter, a sleeve mounted in said chamber having an exterior diameter approximately that of the last-named extension of the chamber, a plurality of jaws pivotally mounted on the sleeve for radial 90 swinging movement, the jaws being segmental in cross section and when disposed in parallel relation defining a bore slightly greater than the diameter of the rod to be operated on, the jaws being adapted to bear against the side wall of the chamber as the sleeve and jaws are forced inward, and means for latching the sleeve from outward movement when the sleeve has been fully forced into the chamber.

13. In a mechanism for upsetting the ends of rods, a rod clamping die having a chamber formed therein, the side walls of which extend inward divergently for a distance, and then converge to a diameter equal 105 to that of the opening of the chamber and then extend inward with a uniform diameter approximately that of the last-named extension of the chamber, a plurality of jaws pivotally mounted on the sleeve for radial 110 swinging movement, the jaws being segmental in cross section and when disposed in parallel relation defining a bore slightly greater than the diameter of the rod to be operated on, the jaws being adapted to bear against the side wall of the chamber as the sleeve and jaws are forced inward, and means for latching the sleeve from outward movement when the sleeve has been fully forced into the chamber, said means including a shank having a detent, the base of the die being formed with an opening to receive said detent, a spring actuated latch mounted upon the die and engageable with said detent, and a spring urging the sleeve toward the entrance end of the chamber.

14. In a mechanism for upsetting the ends of rods, a hollow rod clamping die formed of opposed sections, the sections having co-acting rod seats, means for forcing said sec- 130

tions toward each other to clamp a rod within said seats, a dolly mounted for reciprocation within the hollow clamping die, means for striking blows upon the dolly, and 5 means disposed within the dolly engaging the side face of the rod at all times while it is being upset and supporting the rod against bending, said means being movable into varying angular relation to the axis of 10 the clamping die, as the rod is upset and radially expanded.

15. In mechanism for upsetting the ends of rods, a hollow rod clamping die formed of opposed sections, said sections having co- 15 acting rod seats, means for forcing said sections toward each other to clamp a rod within said seats, a dolly mounted for reciprocation within the hollow clamping die, means for striking blows upon the dolly, 20 and means disposed within the die engaging the side faces of the rod at all times while it is being upset and supporting the rod against bending, said means being longitudinally movable within the die and having 25 portions thereof radially movable into angular relation to the axis of the die.

16. In mechanism for upsetting the ends of rods, a rod clamping die formed in two coacting sections, said sections being formed 30 to provide a chamber and coacting rod clamping seats, the chamber having inwardly divergent walls for a portion of its length, the walls then converging to a diameter equal to the diameter at the entrance 35 of the chamber and then extending rearwardly for a uniform diameter, and means disposed within the rod clamping die for supporting the rod against bending, said

means engaging the side faces of the rod and comprising a sleeve formed of two opposed sections having rod receiving seats and each of said sections of the sleeve being formed with a plurality of radially movable pivoted jaws, the jaws being segmental in cross section and when disposed parallel to the axis of the die defining a bore slightly larger than the rod to be operated on, means operatively engaging the sleeve section with the die for longitudinal movement parallel to the axis of the sleeve, means operatively engaging the free ends of the jaws with the die for movement parallel to the diverging walls of said chamber, a dolly mounted for movement into the open end of the die, means for causing blows to be struck 55 upon the end of the dolly to force it inward, and means for forcing the die sections together into clamping engagement with a rod inserted therethrough, the extremities of the jaws being provided each with a radially extending rib adapted to engage in the radial grooves of the dolly face.

17. In a mechanism for upsetting and radially expanding the ends of rods, a rod clamping member, and means carried by the 60 clamping member engaging the end of the rod to be expanded and supporting said end at all times, said means being movable radially by and with the radial expansion of the rod as its end is upset.

In testimony whereof I hereunto affix my signature in the presence of two witnesses.

OSCAR C. JULIEN.
